United States Patent Office

Des. 185,335
Patented May 26, 1959

185,335

PLAYGROUND STRUCTURE

Don E. Wilkins, Kansas City, Mo.

Application November 12, 1958, Serial No. 53,339

Term of patent 3½ years

(Cl. D34—5)

Fig. 1 is a top plan view of the playground structure, showing the new design;

Fig. 2 is a side elevation from one side;

Fig. 3 is a side elevation from the other side; and
Fig. 4 is an end elevation taken from the shallow end.

I claim:

The ornamental design for a playground structure, as shown.
